UNITED STATES PATENT OFFICE.

HARRY M. PFLAGER, OF ST. LOUIS, MISSOURI, ASSIGNOR TO COMMONWEALTH STEEL COMPANY, OF ST. LOUIS, MISSOURI, A CORPORATION OF NEW JERSEY.

LOCOMOTIVE BED.

Application filed April 13, 1925. Serial No. 22,818.

To all whom it may concern:

Be it known that I, HARRY M. PFLAGER, a citizen of the United States, residing at St. Louis, Missouri, have invented a certain new and useful Improvement in Locomotive Beds, of which the following is a specification, such as will enable others skilled in the art to which it appertains to make and use the same.

10 My invention relates to railway rolling stock and consists in an improved locomotive bed construction particularly adapted for locomotives utilizing one or more steam cylinders located near the center of the locomotive as well as the usual steam cylinders located on the outside of the bed.

15 The object of my invention is to provide an integral structure comprising the frame and cylinders and preferably including the 20 steam supply chambers and boiler saddle also. By making the frame of integral construction I am able to provide a rigid structure which will maintain predetermined dimensions between the cylinders and the drivers. The elimination of the fitting and 25 assembly of many separate parts reduces the expense of producing a complete bed and enables me to provide a structure which for a given weight will be stronger than one 30 produced by the assembly of a number of separate parts.

In locomotives of this type there are a number of places where the clearance between adjacent parts is so small that it is 35 difficult to insert bolts and rivets or to otherwise assemble the parts together and by making the structure integral the necessity of providing clearance for assembling purposes is largely eliminated.

40 In the accompanying drawings which illustrate my invention—

Figure 1 is a top view of a locomotive bed including integral cylinders at its forward ends located on the outside of the frame and 45 also including a cylinder located on the longitudinal center line of the frame. In this bed the locomotive cradle is also formed integral with the bed and in this respect the bed corresponds to that shown in my 50 copending application Serial No. 753,277, filed December 4, 1924.

Figure 2 is a side elevation of the bed shown in Figure 1 with the wheels indicated.

55 Figure 3 is a transverse vertical section

taken through the steam cylinders and supply chambers and drawn on an enlarged scale.

Figure 4 is a longitudinal vertical section taken on line 4—4 of Figure 3. 60

Figure 5 is a vertical transverse section corresponding to Figure 3 but illustrating a modification of my invention.

The bed comprises side frames 1 which are connected at intervals throughout the length of the bed by suitable cross elements 2. These frames terminate at their rear in the cradle frame 3 and are recessed at 4 to provide pedestals for the driving boxes, not shown. The side frames will be braced 65 across the openings 4 by suitable members 5. The forward ends of the side frames have integrally formed therewith cylinders 6, 7 and 8, cylinders 6 and 8 being located on the outside of said frames 1 and cylinder 7 being located between them and above the level of cylinders 6 and 8. Cylinder 7 will be inclined as shown in Figure 4 as is usual with the intermediate cylinder of locomotives having three cylinders. 70

75 Formed integrally with the cylinders are the steam supply chambers 9, 10, and 11 and connecting the steam supply chambers with their respective cylinders are suitable steam passages 12, 13 and 14. Above cylinder 7 are suitable projections uniting to form a saddle 15 on which the front end of a locomotive boiler may be supported. Suitable 80 exhaust passages 16, 17 and 18 will be provided in the casting, all of these passages terminating in an outlet near the center of saddle 15 for the purpose of discharging the exhaust into the smoke box according to established practice. 85

90 With this structure it will be seen that the steam cylinders are rigid with each other and with their respective supply chambers and are rigidly spaced from the drivers and the yokes 29 which mount the valve gear because of the integral structure of the frame between the cylinders and the pedestals for the driving boxes. By making the frame and cradle integral, the boiler supports, indicated at 19 and 20, are maintained in proper relation to the forward boiler support formed by saddle 15 and disadvantages due to the assembly of the cradle and parts mounted thereon with the main frame are eliminated. 95

100 In Figure 5 I illustrate a modification of 110

my invention in which four cylinders are provided, two of these cylinders 21 and 22 being located on the outside of the side frames 23, and two of the cylinders 24 and 25 being located between the side frames. This construction embodies suitable arrangements of the steam supply chambers and the passages from these chambers to the cylinders and from the cylinders to the exhaust. 5 It will be understood that the supply chamber 27 is adapted to supply cylinders 21 and 24 and that supply chamber 28 is adapted to supply cylinders 22 and 25 instead of each steam cylinder having its individual supply chamber as indicated in the structure shown in Figures 1 to 4.

Obviously, the details of construction of the different parts shown as formed integral with the main frame may be varied to suit 20 special circumstances without departing from the spirit of my invention as expressed in the following claims.

I claim:

1. A locomotive bed including a steam cylinder formed integrally with said bed and located centrally thereof.

2. A locomotive bed comprising side frames, and a steam cylinder formed integrally with said side frames and located 30 between them.

3. In a locomotive bed, a longitudinal frame, and a plurality of cylinders formed integrally with said frame and with each other and respectively located at each side 35 of said frame and centrally thereof.

4. In a locomotive bed, side frames, a steam cylinder formed integrally on the outer side of each of said frames, and one or more steam cylinders formed integrally 40 with said side frames and located between them.

5. A locomotive bed including a steam cylinder formed integrally with said bed and located centrally thereof, and a steam 45 supply chamber for said cylinder formed integrally with said bed and cylinder.

6. A locomotive bed comprising side frames and a steam cylinder formed integrally with said frames and located 50 between them and a steam supply chamber for said cylinder formed integrally therewith and located adjacent one of said side frames.

7. In a locomotive bed, a longitudinal frame and a plurality of cylinders formed 55 integrally therewith and with each other and respectively located at each side of said frame and centrally thereof, and an individual steam supply chamber for each of said cylinders formed integrally with said cylinders and frame.

8. In a locomotive frame, side frames, a steam cylinder formed integrally on the outer side of each of said frames and one or 60 more steam cylinders formed integrally with said frames and located between them, and

an individual supply chamber for each of said cylinders formed integrally with said cylinders and frame.

9. In a locomotive bed, a main frame, a steam cylinder located centrally of said frame, and a boiler saddle formed integrally with said frame and cylinder.

10. In a locomotive bed, a main frame, a boiler saddle thereon and one or more steam cylinders beneath said boiler saddle, said 75 frame, saddle, and cylinders being formed integrally.

11. In a locomotive bed, side frames, a boiler saddle extending transversely of said side frames, and one or more steam cylinders formed integrally with said side frames and boiler saddle and located between said side frames and beneath said saddle.

12. In a locomotive bed, a frame, driving box pedestals, and a steam cylinder located 85 between the sides of said frame, said pedestals and cylinder being formed integrally with said frame.

13. In a locomotive bed, a frame, driving box pedestals, a steam cylinder located between the sides of said frame, and steam cylinders located on the outside of said frame, said pedestals and cylinders being formed integrally with said frame.

14. A locomotive bed comprising a frame, driving box pedestals, a boiler saddle, and a steam cylinder located between the sides of said frame beneath said boiler saddle, said pedestals, saddle and cylinder being formed 95 integrally with said frame.

15. In a locomotive bed, a frame, driving box pedestals, a boiler saddle, a steam cylinder located between the sides of said frame beneath said boiler saddle, and steam cylinders located on the outside of said frame, said pedestals, saddle, and cylinders being formed integrally with said frame.

16. In a locomotive bed, a frame, driving box pedestals, a steam cylinder located between the sides of said frame, a steam supply chamber for said cylinder, said pedestals, cylinder, and chamber being formed integrally with said frame.

17. In a locomotive bed, a frame, driving box pedestals, a steam cylinder located between the sides of said frame, steam cylinders located on the outside of said frame, steam supply chambers for each of said cylinders, said pedestals, cylinders and chambers being formed integrally with said frame.

18. In a locomotive bed, a frame, driving box pedestals, a boiler saddle, steam cylinders located between the sides of said frame beneath said saddle, a steam supply chamber for said cylinder, said pedestals, saddle, cylinder, and chambers being formed integrally with said frame.

19. In a locomotive bed, a main frame, a steam cylinder located between the sides of 130

said frame, a saddle above said cylinder, and a cradle, said cylinder, saddle, and cradle being formed integrally with said frame.

20. In a locomotive bed, a main frame, a cylinder located between the sides of said frame, cylinders located on the outside of said frame, a boiler saddle located above the level of said cylinders, and a cradle, said cylinders, saddle, and cradle being formed integrally with said frame.

21. In a locomotive bed, a main frame, a cylinder located between the sides of said frame, cylinders located on the outside of said frame, a boiler saddle located above the level of said cylinders, steam supply chambers for said cylinders, and a cradle, said cylinders, saddle, chambers, and cradle being formed integrally with said frame.

22. In a locomotive bed, side frames, a steam cylinder formed integrally with each of said side frames on the outer side thereof, and a plurality of steam cylinders formed integrally with said side frames and located between them.

23. A locomotive bed comprising side frames and a plurality of steam cylinders formed integrally with said side frames and located between them.

24. A locomotive bed comprising side frames and a plurality of steam cylinders formed integrally with said side frames and located between them, and steam supply chambers for said cylinders formed integrally therewith.

25. In a one-piece casting, a locomotive main frame, a boiler saddle, and a plurality of cylinders beneath said saddle.

26. In a one-piece casting, a locomotive main frame, a boiler saddle, and a plurality of cylinders located centrally of said frame and beneath said saddle.

27. In a one-piece casting, a locomotive main frame, a boiler saddle, and a plurality of cylinders and steam supply chambers beneath said saddle.

In testimony whereof I hereunto affix my signature this 8 day of April, 1925.

H. M. PFLAGER.
